UNITED STATES PATENT OFFICE.

ERNEST ZERWECK, OF OAKLAND, CALIFORNIA.

TRAVELING SPRINKLER.

1,418,047.

Specification of Letters Patent. Patented May 30, 1922.

Application filed June 15, 1920. Serial No. 389,092.

To all whom it may concern:

Be it known that I, ERNEST ZERWECK, a citizen of the United States, residing at Oakland, Elmhurst, in the county of Alameda and State of California, have invented certain new and useful Improvements in Traveling Sprinklers, of which the following is a specification.

This invention relates to improved means for sprinkling large areas of ground, and the invention has for its objects among others to provide an improved sprinkler which will travel backward and forward on a predetermined path, at the same time throwing the water to a considerable distance on each side of said path.

It has for a further object to provide a sprinkler of this general character with simple means whereby the rotation of the sprinkler is utilized to move the carrier for the sprinkler along a track, automatic means being provided for reversing the direction of travel of the said carrier.

I aim further at improvements in the details of construction as will be hereinafter more particularly explained.

Other objects and advantages of the invention will hereinafter appear, and the novel features thereof will be specifically defined by the appended claims.

The invention, in its preferred form, is clearly illustrated in the accompanying drawings, which, with the numerals of reference marked thereon, form a part of this specification, and in which—

Figure 1 is a side view of my improved sprinkler, with portions broken away and parts in section.

Figure 2 is an end view thereof with parts in section.

Figure 3 is a plan view of a detail of construction, with one of the shafts of one of the gears shown in cross section.

Figure 4 is an enlarged elevation showing the clutch and the reversing mechanism.

Figure 5 is a detail in elevation showing a modified form of the hose-winding reel.

Like numerals of reference indicate like parts throughout the several views.

Referring to the drawings,

1 indicates a raised track supported by suitable means as the posts 2, upon which can run wheels 3 of a carriage 4, having means supporting on ball bearings 6 a rotary sprinkler 7 of ordinary construction. The central vertical pipe 8 of said sprinkler

communicates through a packing 9 with a vertical pipe 10 which is connected by a coupling 11 with a flexible pipe 12 which is wound upon a spring-actuated drum 13 60 rotatably mounted in supports 14 on the ground.

The vertical pipe 8 of said sprinkler carries a pinion 16 which meshes with a gear wheel 17 on a vertical shaft 18 carried by the carriage 4 and having thereon a pinion 19 carrying a clutch member 20 and loose on the vertical shaft 18 but caused to rotate therewith by means of a clutch 21 rotating with said shaft 18. Said pinion 19 meshes with a gear wheel 22 upon a vertical shaft 23 mounted in bearings 24 carried by the carriage 4, said shaft 23 being extended, as at 25, and also carrying a gear wheel 26 which meshes with a horizontally extending rack 27 secured to the posts 2. Thereby said shaft 23 and carriage 4 are caused to move longitudinally, carrying therewith the sprinkler 7. A lever 28 operating the clutch extends on both sides 80 of the clutch, as shown in Figure 4, and each end of the lever, in turn, is caused to engage one of two inclined surfaces or wedges 29 at the ends of the path of the carriage 4, thereby shifting the clutch from 85 one operating position to the other. A weight 30 adjustably secured on the lever 28 balances the weight of the clutch, so that the lever remains in any position to which it has been moved. In the other 90 operating position, the operative connection is broken between the shaft 18 and the pinion 19 and an operative connection is closed between the shaft 18 and a pinion 31 thereon which meshes with a gear wheel 95 32 on a vertical shaft 33 rotating in bearings 34 carried by the carriage, on which shaft 33 is secured an upper gear wheel 36 which meshes with the gear wheel 22 and thereby rotates said gear wheel in the opposite 100 direction to its previous direction.

The winding drum or reel may be weight actuated, instead of spring-actuated, and in Figure 5 I have shown one form of such modified form of winding mechanism, 105 wherein, in lieu of the spring for actuating the drum, I have shown a weight 37, attached to one end of a cord or the like 38 which runs over the pulleys 39 and 40, suitably supported by the upright 41 and 110 the lateral member 42, suitably braced, as at 43, the other end of the cord or liga-

ment 38 being wound upon the drum in a well-known manner.

I also may provide roller supports 44 for the running of the hose, as seen in Figure 1, which may be supported in proper position in any suitable manner, as by the uprights 45 rising from the rack, as seen in said view. These roller supports, however, may not always be present, although desirable in some instances as they prevent sagging of the hose when being run out for long distances.

What is claimed as new is:—

1. A rotatably mounted drum, a track, a carrier mounted to travel on said track, a rotatably mounted sprinkler carried by the carrier, a hose carried by the carrier and wound upon said drum to directly rotate the sprinkler, a horizontally extending rack, and gearing interposed between the rack and sprinkler for moving said carrier along the track.

2. A rotatably mounted drum, a track, a carrier mounted to travel on said track, a rotatably mounted sprinkler carried by the carrier, a hose carried by the carrier and wound upon said drum to directly rotate the sprinkler, a horizontally extending rack, gearing interposed between the rack and sprinkler for moving said carrier along the track, and means for automatically re-

versing the direction of travel of the carrier.

3. The combination of a rotary sprinkler, a carriage therefor, a track upon which said carriage travels, a flexible hose connected to the rotary sprinkler, the sprinkler being rotated directly by the flow of the water through the hose and means whereby the rotation of the sprinkler moves said carriage along said track comprising a longitudinally extending rack and a gear wheel actuated by the rotation of the carriage and pressing against said rack, and gearing actuated by said gear wheel for rotating the sprinkler.

4. The combination with a rotary sprinkler, a carriage therefor, a track upon which said carriage travels, a flexible hose connected to the rotary sprinkler, the sprinkler being rotated directly by the flow of the water through the hose, means whereby the rotation of the sprinkler moves said carriage along said track comprising a longitudinally extending rack, a gear wheel operatively connected with the axle of the sprinkler meshing with said rack and an operative gear connection between the sprinkler and the gear wheel whereby the rotation of the former rotates the latter.

In testimony whereof I affix my signature.

ERNEST ZERWECK.
